UNITED STATES PATENT OFFICE.

HERMAN GOULD, OF NEW YORK, N. Y., ASSIGNOR OF TWO-THIRDS TO FRANK ACKERMANN AND JOHN GEEING, BOTH OF NEW YORK, N. Y.

FEEDING GAUGE FOR EMBOSsing MACHINES.

Application filed December 27, 1921. Serial No. 525,238.

To all whom it may concern:

Be it known that I, HERMAN GOULD, a resident of New York city, county and State of New York, and a citizen of the United 5 State of America, have invented certain new and useful Improvements in Feeding Gauges for Embossing Machines, of which the following is a specification.

This invention relates to improvements in 10 feeding gauges, more particularly for embossing machines for belts and the like. My invention is intended for use in connection with rotary embossing elements which act to not only emboss belts, but also to feed 15 same. My improved feeding gauge is arranged for use more particularly in connection with belts having pointed ends, the said ends having curved edges.

I will now proceed to describe my invention 20 in detail, the novel features of which I will point out in the appended claims, reference being had to the accompanying drawing, wherein:—

Fig. 1 illustrates, in side elevation, an embodiment of my invention;

Fig. 2 is an enlarged fragmentary plan view of the feeding gauge;

Fig. 3 is an enlarged edge view thereof; and

Fig. 4 is a fragmentary view of a belt having scoring adjacent the edges thereof.

For the purposes of illustration, I have embodied my invention in the form of a machine to score belts adjacent the edges thereof, although it should be understood that instead of scoring the belts, I may emboss same by employing the proper dies. As herein arranged, the device is made up of scoring dies or disks 5 and 6 carried by a 35 shaft 7 connected by gears (not shown) to a second shaft 8 carrying a disk 9 to act as a backing for the belts when the disks 5 and 6 are acting upon same. The shaft 8 is provided with a belt-wheel 10 to carry 40 a driving belt (not shown). The numeral 12 indicates a casing for the gears, to which is attached a table 13 to support the gauges 14 and 15 which act to guide the belts a portion of one of which is indicated by 17. 45 The disks or dies 5 and 6 act to score the belts adjacent the edges thereof as indicated by 18 and 19. The gauges 14 and 15 each consists of a plate 20 carried by a bracket 21, said plate being spaced from the table 13 50 to provide for the adjustable mounting of

rollers 22 and 23 on plate 20. In this instance, the rollers 22 and 23 are slidably mounted in slots 24 and 25, respectively, in plate 20. Each roller 22 and 23 is connected by a link to a slidably mounted anchor which 60 when shifted or adjusted will move or adjust the rollers 22 and 23 longitudinally of the slots 24 and 25 to prepare the gauge for belts of different widths.

Referring to Fig. 2, it will be seen that 65 rollers 23 and 24 are connected to the shiftable anchor 26 by links 27 and 28, respectively. The anchor 26 consists of a sliding plate 29 carrying a threaded stud 30, which passes through the slot 31 in plate 20, and a stud 32 which is engaged by the adjacent ends of links 27 and 28. The anchor 26 is held in adjusted positions longitudinally of the slot 31 by a binding nut 33. Each 70 roller 22 and 23 is rotatably mounted on a stud 34 which passes through its respective slot. Each stud 34 has connected thereto a corresponding link, by which means, when anchor 26 is moved, the rollers 22 and 23 will be moved longitudinally of the slots 24 75 and 25. Adjacent the slot 24, I provide index marks 35 to enable an operator to set rollers 22 and 23 for belts of different widths. In combination with each gauge, I employ a 80 stop 36 adjustably mounted on an arm 37 pivotally connected to the fin or guide 38 on the table 13. The stops 36 act to guide the belts while being initially presented, as indicated by full lines in Fig. 2, and also after the belts have been fed sufficiently to 85 cause the disks 5 and 6 to score the belts in parallelism with the side edges thereof. The gauge at the left of fin or guide 38 will be used while scoring line 19, and gauge at the right of said fin or guide will be used while 90 scoring line 18. Each stop block 36 will be provided with an inclined end 39, the lower edge 40 of which is preferably rounded in order that said blocks will rise when the 95 belts are forced to the left while in gauge 14 and to the right while in gauge 15.

To score a belt, the pointed end 41 thereof, which has rounded edges, will be placed in a gauge, 14 or 15, as indicated by full lines in Fig. 2, or at an angle relative to the axis 105 of the shaft 7, with one curved edge of end 41 in contact with fin 38, the roller 22 being set or positioned to contact with the opposite curved edge of end 41. As soon as disks 5 and 6 start to rotate, the belt will be drawn 110

in the direction of arrow 42 and caused to move circumferentially of the roller 22 until it assumes the dotted line position in Fig. 2. During the turning of the belt circumferentially of roller 22, the curved portion 43 of score line 19 will be produced. After score line 19 has been completed, the belt will be placed in gauge 15 and score line 18 produced.

10 After a belt has been inserted, as indicated by full lines in Fig. 1, the disk 5 will draw it, as has been stated, in the direction of arrow 42, causing it to revolve around the roller 22. The point of contact of the edge 15 of the belt, opposite the fin or guide 38, with the peripheral surface of roller 22, acts as a pivot point about which the belt will move to allow disk 5 to score the curved portion 43. To accommodate belts of different 20 widths roller 22 will be adjusted toward or away from the fin or guide 38. For the same reason, the block 36 will be adjusted longitudinally of slot 44 in arm 37. My improved feeding gauge is especially intended 25 to score or emboss straps having pointed ends, the said pointed ends having curved edges. The rollers 22 will be positioned to contact with an edge of a strap at the radial point of the curvature of the opposite 30 edge of the strap, or approximately so. The roller 23 functions to maintain the strap in parallelism with the fin or guide 38 after the strap has been moved from the full to the dotted line position, Fig. 1. Roller 22 also 35 acts in the same capacity. The blocks 36 act to facilitate the initial positioning of the belts and also to cooperate with guide 38 after the belts have been moved into contact with said guide. After a belt has been 40 moved into contact with guide 38, it will lie between said guide and heel 45 of its adjacent block. During the movement of a belt from its initial position to its final position against guide 38, the blocks 36 will 45 rise, being forced upwardly by the belts.

What I claim and desire to secure by Letters Patent is:—

1. In combination with a rotary embossing element, a gauge for articles having 50 pointed ends with curved edges consisting of a guide element and a pivot element, arranged to contact with one edge of the article to be acted upon by the embossing element, at approximately the radial point of 55 the curvature of the opposite curved edge of the pointed end, whereby said article can be rotated about said pivot point while the embossing element is acting upon said article adjacent the curved edge opposite the 60 pivot point.

2. In combination with a rotary embossing element, a gauge for belts having pointed ends with curved edges, arranged for the initial positioning of a belt at an acute 65 angle relative to the axis of the embossing

element, said gauge having a pivotal point contacting with one edge of said belt about which said belt is rotated, to a position at approximately a right angle to the axis of the embossing element while said embossing 70 element is acting upon said belt adjacent the curved edge opposite the pivot point.

3. In combination with a rotary embossing element, a gauge for belts having pointed ends with curved edges, arranged for the initial positioning of a belt at an acute angle relative to the axis of the embossing element, said gauge having an adjustable pivotal point contacting with one edge of said belt about which said belt is rotated, to a position at approximately a right angle to the axis of the embossing element while said embossing element is acting upon said belt adjacent the curved edge opposite the pivot point. 75

4. In combination with a rotary embossing element, a gauge for belts having pointed ends with curved edges, arranged for the initial positioning of a belt at an acute angle relative to the axis of the embossing 80 element, said gauge having an adjustable roller contacting with one edge of said belt about which said belt is rotated, to a position at approximately a right angle to the axis of the embossing element while said embossing 85 element is acting upon said belt adjacent the curved edge opposite the roller. 90

5. In combination with a rotary embossing element, a gauge for belts having pointed ends with curved edges consisting of a 95 table, a guide carried thereby disposed at a right angle to the axis of the embossing element, and a plurality of rollers adjacent said guide, one of said guides being positioned, relative to the embossing element, to 100 act as a pivot point to enable the belts to be moved in a rotary direction while said belts, adjacent the curved edges, are being embossed.

6. In combination with a rotary embossing element, a gauge for belts having pointed ends with curved edges consisting of a 105 table, a guide carried thereby disposed at a right angle to the axis of the embossing element, a plurality of rollers adjacent said 110 guide, one of said guides being positioned, relative to the embossing element, to act as a pivot point to enable the belts to be moved in a rotary direction while said belts, adjacent the curved edges, are being embossed, 115 and means to adjust said rollers relative to the guide. 120

7. In combination with a rotary embossing element, a gauge for belts having pointed ends with curved edges consisting of a 125 table, a guide carried thereby disposed at a right angle to the axis of the embossing element, a plurality of rollers adjacent said 130 guide, one of said guides being positioned, relative to the embossing element, to act as

a pivot point to enable the belts to be moved in a rotary direction while said belts, adjacent the curved edges, are being embossed, and means to adjust said rollers relative to 5 the guide, said rollers being in alinement and disposed in a line parallel to the said guide.

8. In combination with a rotary embossing element, a gauge for belts having pointed ends with curved edges consisting of a 10 table, a guide carried thereby disposed at a

right angle to the axis of the embossing element, a plurality of rollers adjacent said guide, one of said guides being positioned, relative to the embossing element, to act as 15 a pivot point to enable the belts to be moved in a rotary direction while said belts, adjacent the curved edges, are being embossed, and means to simultaneously adjust said rollers relative to the said guide.

HERMAN GOULD.
